(57) **CLAIM**

The ornamental design for the trailer hitch, as shown and described.

DESCRIPTION

FIG. 1 is a perspective view in a driving direction on the front side and right hand side of the trailer hitch mounted on a portion of a cross beam in an operative position according to an embodiment;

FIG. 2 is a front view thereof;

FIG. 3 is a right hand side view thereof;

FIG. 4 is a back view thereof;

FIG. 5 is a left hand side view thereof;

FIG. 6 is top view thereof;

FIG. 7 is a bottom view thereof;

FIG. 8 is a perspective view of the same trailer hitch as shown in FIG. 1 in the same operative position, but not mounted on a portion of a cross beam;

FIG. 9 is a front view of FIG. 8;

FIG. 10 is a right hand side view of FIG. 8;

FIG. 11 is a back view of FIG. 8;

FIG. 12 is a left hand side view of FIG. 8;

FIG. 13 is top view of FIG. 8;

FIG. 14 is a bottom view of FIG. 8;

FIG. 15 is a perspective view of the same trailer hitch as shown in FIG. 1 mounted on a portion of a cross beam, but in a rest position rather than the operative position shown in FIG. 1;

FIG. 16 is a front view of FIG. 15;

FIG. 17 is a right hand side view of FIG. 15;

FIG. 18 is a back view of FIG. 15;

FIG. 19 is a left hand side view of FIG. 15;

FIG. 20 is top view of FIG. 15;

FIG. 21 is a bottom view of FIG. 15;

FIG. 22 is a perspective view of the same trailer hitch as shown in FIG. 1, but shown in the same rest position as in FIG. 15, and without being mounted on a portion of a cross beam like FIG. 8;

FIG. 23 is a front view of FIG. 22;

FIG. 24 is a right hand side view of FIG. 22;

(Continued)

FIG. 25 is a back view of FIG. 22;
 FIG. 26 is a left hand side view of FIG. 22;
 FIG. 27 is top view of FIG. 22; and,
 FIG. 28 is a bottom view of FIG. 22.
 The dot-dashed break lines shown in FIGS. 1-7, and 15-21 indicate a symbolic break in length of a tubular cross beam support to which the trailer hitch is mounted. The break lines and the appearance of any portion of the article between the break lines forms no part of the claimed design.
 The dashed broken lines in FIGS. 1-7, and 15-21 represent structures or features that form no part of the claim design.
